UNITED STATES PATENT OFFICE.

EDWARD F. FLANAGAN, OF WASHINGTON, DISTRICT OF COLUMBIA.

CONDIMENT-HOLDER.

1,110,383.

Specification of Letters Patent. Patented Sept. 15, 1914.

Application filed July 30, 1913. Serial No. 782,081.

To all whom it may concern:

Be it known that I, EDWARD F. FLANAGAN, a citizen of the United States, residing at Washington, District of Columbia, have 5 invented certain new and useful Improvements in Condiment-Holders, of which the following is a specification, reference being had to the accompanying drawings.

This invention relates to condiment holders such as are used for containing salt, pepper, and similar pulverulent material, the primary object of the invention residing 10 in the provision of improved means for agitating the contents of the holder when 15 the same is damp so that it will freely pass through the perforated end thereof.

It is a further object of the present invention to provide a holder of the above character having a perforated end wall provided 20 with an inclined or sloping inner face and a revoluble scraping element arranged in the holder for engagement with said inclined face, whereby the granular material which may adhere thereto will be readily 25 removed.

The invention has for still another object to provide a device of the above character which may be easily and quickly cleaned 30 and filled, comprises but few parts in its construction, and can, therefore, be produced at comparatively small manufacturing cost.

With the above and other objects in view, this invention consists in the novel features 35 of construction, combination and arrangements of parts that I shall hereinafter fully describe and claim.

For a full understanding of the invention, reference is to be had to the following 40 description and accompanying drawing, in which—

Figure 1 is a perspective view of a condiment holder embodying the present invention. Fig. 2 is a longitudinal section thereof. Fig. 3 is a section taken on the line 45 3—3 of Fig. 2. Fig. 4 is a detail perspective view of the agitator removed.

Referring in detail to the drawing, 5 designates the body of the holder which may 50 be constructed of metal, glass, china, or other suitable material, and is preferably

of longitudinally tapering cylindrical form, the diameter of the holder gradually increasing from its upper to its lower end. The lower end of the holder body 5 is exteriorly threaded, as indicated at 6, to receive the threaded extension 7 of a metal sleeve 8. This sleeve is flanged at its opposite end, as at 9, and suitably secured to the end and outer face of the bottom section 10 55 of the holder. This bottom section is constructed of the same material as the body 5. A paraffin disk 11 is arranged between the bottom section 10 and the opposed end of the body 5 and provides an air and water- 60 tight closure for said body section. This disk is provided with a central opening 12 for a purpose which will be later explained. At the other or upper end of the holder 5, the same is closed by the integral end wall 70 13 which is perforated, as at 14. The bottom face of this perforated top of the body 5 is beveled or inclined, as indicated at 15 from its center to its outer edge.

16 designates the stem or rod of an agitator which is centrally disposed within the holder and has its upper end engaged in a central opening 17 provided in the top wall 13. The lower end of this stem is adapted to extend through the opening 12 in the 80 paraffin disk 11 and is provided with a squared portion 18 and a threaded terminal 19. Upon the squared portion 18 of the stem a wing nut 20 is adapted to be fitted and is securely held thereon by means of the 85 nut 21 engaged upon the threaded extremity 19 of said stem. Adjacent the upper end of the rod or stem 16, the same is provided with the oppositely extending blades 22. These blades extend upwardly at a slight in- 90 clination from their inner to their outer ends and said outer ends of the blades are connected to the stem 16 inwardly from the inner ends of the blades by means of the wires 23. Additional wires 24 are fixed to 95 the stem 16 and connected at their opposite ends to the respective wires 23. The upper edges of the blades 22 are in scraping contact with the inclined bottom face 15 of the top 13.

100 It will thus be apparent that when the stem or rod 16 is rotated, said blades will

scrape the salt or other granular material from the inclined face which may have adhered thereto, owing to a damp or wet condition of the same. Thus clogging of 5 the apertures 14 is obviated. At the same time, the wires 23 and 24 serve to thoroughly break up or divide the material into a finely comminuted state. Bowed or curved wires 25 are also fixed to the stem 16 below 10 the point of attachment of the wires 23 thereto, said wires 25 being arranged upon diametrically opposite sides of the stem. These wires provide additional means for 15 breaking up the lumps of salt, or other material, so that the same will freely flow through the apertures 14 in the end of the holder. In the preferred embodiment of 20 my invention, I preferably employ four of the scraping blades 22 which extend radially from the stem 16, but it will of course be obvious that a greater or less number of 25 these blades may be used if desired. This statement will also apply with equal force to the additional wires 25 carried by said stem.

Adjacent the lower end of the rod or stem 16 of the agitator the same is provided with an annular shoulder 26 which is of greater diameter than the opening 12 of 30 the paraffin disk 11 and securely closed at said opening when the bottom section 10 of the holder is connected to the lower end of the body 5 thereof. Thus the escape of the material through this opening is 35 prevented and the entrance of moisture into the interior of the holder is also obviated.

From the foregoing, it is thought that the construction and purpose of my invention will be clearly and fully understood. 40 In assembling the several parts, the upper end of the stem or rod 16 is engaged in the central opening 17 in the perforated end wall 13 of the holder, the scraping blades 22 being engaged with the inner sloping 45 face 15 of said end wall. The end section is then placed in position, the sleeve 7 being threaded upon the lower end of the holder body 5 while the stem 16 is disposed through the opening 12 of the paraffin disk 11. 50 When the end of the section 10 is tightly engaged against the end of the body 5, the shoulder 26 on the agitator rod will also be in close frictional contact with the upper surface of the paraffin disk 11. This friction, however, is not sufficient to prevent 55 manual rotation of the agitator. It will be seen that the hollow lower section 10 of the holder is of sufficient depth to entirely inclose the lower end of the stem or rod 60 16 which projects through the opening in the disk 11. When it is desired to agitate the contents of the holder, the operator simply turns the rod 16 by means of the wing nut 20, thus scraping the adhering particles

from the bottom face of the top 13, as above 65 explained, and breaking up the lumps of salt or other material by means of the wires 23 and 24 and 25.

When a free and unrestricted flow of the salt or other material through the perforations 14 is desired, the same may be obtained by simply turning the sleeve 8 upon the lower end of the holder body to move the stem 16 longitudinally and disengage the scraping blades 22 from the inner face 75 of the perforated wall 13. This adjustment may be very easily and quickly made and an independent adjustment of the stem or its temporary removal from the holder is unnecessary. It will further be appreciated 80 that by connecting the outer ends of the blades 22 to the stem by means of the wires 23 and providing the bracing wires 24 between said wires 23 and the stem, an effective brace for the scraping blades is produced 85 so that when the agitator is removed from the holder in order to clean the latter, danger of distortion or injury to the blades 22 is greatly minimized.

A condiment holder comprising the above 90 described features is highly efficient and serviceable in practical use, and assures a free flow of the salt or other condiment under all conditions, and, owing to its simplicity, may be produced at small manufac- 95 turing cost. The several parts may be easily and quickly disassembled so that the interior of the holder may be thoroughly cleaned.

While I have shown and described the pre- 100 ferred construction and arrangement of the several elements employed, it will be obvious that my invention is susceptible of considerable modification without departing from its essential features or sacrificing any of 105 the advantages thereof.

What I claim, is:

1. The combination with a condiment holder having a perforated end wall, of an agitator rotatably mounted in said holder 110 and including a central stem, a plurality of blades radiating from the stem and having scraping engagement with said perforated end wall, and curved wires connecting the outer extremities of said blades to the stem, 115 said wires serving to brace the blades and also operating to break up the condiment into a comminuted state.

2. The combination with a condiment holder having a perforated end wall, of an 120 agitator including a central stem rotatably mounted at one of its ends in said perforated end wall, a plurality of radiating blades fixed at their inner ends to the stem and having scraping engagement with the per- 125 forated wall of the holder, wires connecting the outer extremities of said blades to the stem, additional radially disposed wires con-

necting the latter wires to the stem, said wires bracing the blades and preventing their distortion by contact with the end wall of the holder in the longitudinal movement of the agitator stem with respect thereto, and an additional series of bowed wires secured to the stem inwardly of said first-named wires, all of said wires operating to

divide the condiment into a comminuted state when the agitator is rotated. 10

In testimony whereof I hereunto affix my signature in the presence of two witnesses.

EDWARD F. FLANAGAN.
